UNITED STATES PATENT OFFICE.

CHARLES S. CHRISMAN, OF WEST CHESTER, PENNSYLVANIA, ASSIGNOR TO THE UNITED GAS IMPROVEMENT COMPANY, OF PHILADELPHIA, PENNSYLVANIA, A CORPORATION OF PENNSYLVANIA.

OIL-Injector FOR WATER-GAS APPARATUS.

1,238,071.

Specification of Letters Patent. Patented Aug. 21, 1917.

Application filed October 11, 1916. Serial No. 125,121.

To all whom it may concern:

Be it known that I, CHARLES S. CHRISMAN, a citizen of the United States, and a resident of West Chester, in the county of 5 Chester and State of Pennsylvania, have invented a certain new and useful Oil-Injector for Water-Gas Apparatus and the like, of which the following is a specification.

10 The principal objects of the present invention are first to provide for insuring the protection of oil nozzles used intermittently for injecting oil into a heated region from the deleterious effects of heat when the oil 15 is turned off, and second, to provide for projecting and retracting an oil nozzle in automatic and contemporaneous response to the control of the oil supply and in respect to a region of heat that would be injurious to 20 it, especially in the absence of oil, so that the nozzle is certainly supplied with oil when 25 propelled into a heated region, such as the interior of the carbureter of a water gas set, and is retracted from the heated region when and as the oil supply is cut off or discontinued.

The foregoing objects and others which 30 will hereafter appear in this description are accomplished by mechanism or means of 35 which embodiments are selected for the sake of explanation and illustration in the accompanying drawings in which

Figure 1, is a view, partly in section and partly in elevation, illustrating an embodiment of apparatus containing features of 40 the invention, and

Fig. 2, is a similar view illustrating a modification.

Referring more particularly to Fig. 1, of 45 the drawings, 1, is a cylinder provided with a stop 2, and having one of its ends closed as by a cylinder-head 6, provided with handles 7. 12, is a connection communicating with the cylinder near its closed end and 50 provided with valves 13 and 13^a, the former for oil and the latter for steam which may be used for purging purposes. 9 and 11, are valve elements interconnected for a limited range of relative movement into piston-forming position as shown and into fluid-way forming position. The valve element 9, is tubular and is provided with an internal valve seat formed on the ring 10, which in

use is rigidly connected with the element 9. The other valve element 11, consists of a 55 disk-valve confined in the tubular valve element 9, so as to coöperate with the internal valve seat and to be movable in respect to the element 9. 8, is an oil nozzle connected so as to communicate with the interior of 60 the valve element 9. As shown this is accomplished by the pipe 16, connected with the element 9, and with the nozzle. The valve element 11, is connected by a rod 3, with a weighted lever mechanism arranged 65 at the closed end of the cylinder 1. This weighted mechanism is shown to comprise weighted arms 5, pivotally connected with the rod 3, and with links 4, and which in turn are pivoted to the lugs 7. The weighted 70 lever mechanism therefore acts upon the rod 3, in a straight line. 15, is a base to which the cylinder is connected by a prolongation of the cylinder or sleeve 14.

It may be assumed that *a*, is the top wall 75 of the carbureter of a water gas set because oil is sprayed into the carbureter intermittently and because the temperature of the interior of a carbureter is such that it would deleteriously affect the nozzle 8, if the latter were not supplied with oil and was permitted to project into said chamber. In the absence of oil, the weighted lever mechanism operates to put the valve elements 9 and 11, into position for forming a piston and to 80 draw them toward the closed end of the cylinder, thus retracting the nozzle 8, out of the heated zone or region. When oil is admitted to the cylinder 1, as by opening the valve 13, the pressure of the oil overcomes the 85 action of the weighted lever mechanism and the oil drives the elements 9 and 11, in piston-forming position outward, thus projecting the nozzle 8. At the end of this outward stroke the valve element 9, abuts 95 upon the stop 2, and the valve element 11, clears its seat so that the oil passing through the tubular valve element 9, past the disk-valve element 11, reaches the nozzle 8, as it arrives in its projected position and so the 100 oil flowing through the nozzle protects it from the deleterious effect of heat. When the valve 13, is closed there is no longer hydrostatic pressure in the cylinder and whatever oil may be contained in the cylinder in 105 leaking out past the valve 11, permits the

weighted lever mechanism to retract the nozzle 8, and parts connected therewith to their initial position before the lapse of sufficient time for causing injury to the nozzle 8, by exposure to heat without a supply of oil. A pin-hole 11^a, may be provided in order to insure sufficient leakage and when present it is too small to interfere with the described piston action on the outward stroke. When steam is introduced by opening the valve 13^a, the operation of the parts is as above described.

From the foregoing description it is evident that at the end of the outward stroke of the piston the nozzle is projected and a port or by-pass is opened in order to supply the nozzle with fluid from the cylinder. In Fig. 2, this result is also accomplished and the construction and arrangement of the modification shown in that figure are the same as shown in Fig. 1, except that a spring 5^a, is illustrated instead of the equivalent weights, and the piston 17, is constructed as a unitary structure, or of parts relatively immovable in operation, and use is made of a port or ports 18, adapted to form in connection with a passage 19, in the piston a by-pass around the piston only when in its outward position.

It will be obvious to those skilled in the art to which the invention relates that modifications may be made in details of construction and arrangement without departing from the spirit of the invention so that the latter is not limited as to those matters or in any way further than the prior state of the art and the appended claims may require.

What I claim is:

1. An oil injector for water gas apparatus and the like comprising the combination of a cylinder closed at one end and having a valved inlet, retracting mechanism, a piston element operatively connected with the retracting mechanism, a nozzle connected with the piston element and projected and retracted thereby, and by-pass provisions from the cylinder to the nozzle and opened by the outward and closed by the inward stroke of the piston, substantially as described.
2. An oil injector for water gas apparatus and the like comprising the combination of a cylinder closed at one end and provided with a stop, a weighted lever mechanism arranged at the closed end of the cylinder, an oil nozzle arranged at the open end of the cylinder, a tubular valve element movable in the cylinder for coöperation with the stop and provided with an internal valve seat and connected with the nozzle, and a disk-valve element connected with the weighted mechanism and inclosed in the tubular valve ele-

ment inside its valve seat, substantially as described.

3. An oil injector for water gas apparatus and the like comprising the combination of a cylinder, a limiting stop, a retracting mechanism adapted to be overcome by the oil pressure, a nozzle to be projected and supplied with oil and automatically retracted when the oil supply is cut off, and valve elements arranged in the cylinder and interconnected for limited range of relative movement into cylinder forming and fluid-way forming positions and whereof one is connected with the retracting mechanism and the other is connected with the nozzle and adapted to coöperate with the limiting stop, substantially as described.

4. An oil injector for water gas apparatus and the like comprising the combination of valve elements interconnected for limited relative movement into piston-forming and fluid-way forming positions, a cylinder in which said elements, in piston-forming position, make outward strokes under oil pressure, a stop coöperating with the elements at the limit of an outward stroke to position them in fluid-way-forming position, a retracting gear connected with the elements and tending to put them in piston-forming position and to cause them to make outward strokes in the absence of the fluid pressure, an oil nozzle connected with the valve elements and projected and retracted and automatically feed-governed thereby, and an oil admission valve for the injector.

5. An oil injector for water gas apparatus and the like comprising the combination of a cylinder, a limiting stop, a retracting mechanism adapted to be overcome by oil pressure, a nozzle to be projected and supplied with oil and automatically retracted when the oil supply is cut off, valve elements arranged in the cylinder and interconnected for limited range of relative movement into cylinder forming and fluid-way forming positions and whereof one is connected with the retracting mechanism and the other is connected with the nozzle and adapted to coöperate with the limiting stop, a sleeve constituting a prolongation of the cylinder beyond the limiting stop, and a base connected with said sleeve, substantially as described.

6. An oil injector for water gas apparatus and the like comprising the combination of an oil supply, a normally retracted nozzle, and fluid actuated mechanism responsive to the oil supply and adapted to project the nozzle, substantially as described.

CHARLES S. CHRISMAN.
